UNITED STATES PATENT OFFICE.

HENRY C. CURNOW, OF COLUMBIA, PENNSYLVANIA.

COMBINED JAR CAP AND OPENER.

No. 905,664.

Specification of Letters Patent.

Patented Dec. 1, 1908.

Application filed September 10, 1908. Serial No. 452,483.

To all whom it may concern:

Be it known that I, HENRY C. CURNOW, a citizen of the United States, residing at Columbia, in the county of Lancaster and State of Pennsylvania, have invented certain new and useful Improvements in Combined Jar Caps and Openers; and I do declare the following to be a full, clear, and exact description of the invention, such as will enable others skilled in the art to which it appertains to make and use the same.

This invention relates to improvements in combined jar caps and openers.

The object of the invention is to provide a combined milk jar cap and opener whereby the ordinary pasteboard closing disk may be readily removed and a sanitary, non-corrosive tight-fitting cover provided which may be readily removed from and replaced on the jar when desired.

With this and other objects in view, the invention consists of certain novel features of construction, combination and arrangement of parts as will be described and particularly pointed out in the appended claims.

In the accompanying drawing, Figure 1 is a vertical sectional view of the upper end of a milk jar showing my improved cap applied thereto in position to remove the pasteboard closing disk; Fig. 2 is a similar view showing the cap applied to the jar to close the latter; and Fig. 3 is an enlarged perspective view of the cap.

In the accompanying drawing, 1 denotes a cap, which is formed of aluminum or similar non-corrosive metal. The cap comprises an outer, downwardly-projecting flange, 2, which conforms to and is adapted to be engaged with the upper edge of the jar neck, as shown. The flange, 3 is provided with an outwardly-turned lower edge, 3, which facilitates the engagement with and disengagement of the flange, 2, from the edge of the jar neck, and also serves to strengthen said edge, and to provide a smooth finish for the same.

The cap, 1, is provided with a centrally-depressed or downwardly-projecting portion, 4, which is adapted to fit into the annular groove or recess formed in the inner edge of the mouth of the jar and to provide a fluid-tight engagement with said groove, which, together with the engagement of the upper end of the jar neck, forms a double seal or closure for the jar.

Secured to the center of the depressed por-

tion, 4, of the cap and projecting downwardly a suitable distance therefrom is a prong or barb, 5, having a triangular arrow-shaped head, 6, said prong or barb being adapted to be forced through the pasteboard disk, 7, which is usually employed for temporarily closing milk jars or bottles after being filled for delivery. The prong or barb is forced through the pasteboard disk by the engagement of the cap, 1, with the upper end of the jar neck, as clearly shown in Fig. 1 of the drawing, after which the cap is pulled off the neck of the jar, carrying with it the pasteboard disk, 7, the cap thus forming a convenient means for removing said disk. After the disk has been thus removed from the jar, it is disengaged from the barb or prong, 5, and the cap then replaced upon the neck of the jar to serve as a cover therefor.

The cap is preferably formed of aluminum, but may be constructed of any non-corrosive metal, and is preferably of such thickness as to provide sufficient elasticity or yielding qualities to the flange, 2, thereof, to permit the latter to be sprung into and out of engagement with the rounded outer edge of the jar neck, said cap thus forming an efficient closure for the jar which may be readily engaged with and disengaged therefrom when desired.

From the foregoing description, taken in connection with the accompanying drawing, the construction and operation of the invention will be readily understood without requiring a more extended explanation.

Various changes in the form, proportion and the minor details of construction may be resorted to without departing from the principle or sacrificing any of the advantages of the invention as defined in the appended claims.

Having thus described my invention, what I claim as new and desire to secure by Letters-Patent, is:

1. A device of the class described comprising a metallic cap having a centrally depressed portion to fit into the mouth of the jar, and an annular flange to engage the outer edge of the upper end of the jar neck, and means carried by said cap to engage the pasteboard closing disk of the jar to facilitate the removal thereof.

2. In a combined jar cap and opener, a cap having a centrally depressed closing portion adapted to be engaged with and seat in the open end or mouth of the jar to form an

inner closure therewith, and an annular downwardly-projecting resilient flange adapted to be sprung into engagement with the outer edge of the upper end of the jar neck, 5 and a barb carried by said cap and adapted to be forced through and thereby connected with the pasteboard closing disk of the jar to facilitate the removal of said disk.

In testimony whereof I have hereunto set my hand in presence of two subscribing 10 witnesses.

HENRY C. CURNOW.
